US00D938836S

(12) **United States Design Patent** (10) **Patent No.:** **US D938,836 S**
Matsubayashi et al. (45) **Date of Patent:** **** Dec. 21, 2021**

(54) **TEMPERATURE CONTROL DEVICE**(71) Applicant: **SHINWA CONTROLS CO., LTD.**,
Kawasaki (JP)(72) Inventors: **Shuya Matsubayashi**, Kawasaki (JP);
Kazushige Takahira, Kawasaki (JP)(73) Assignee: **SHINWA CONTROLS CO., LTD.**(**) Term: **15 Years**(21) Appl. No.: **29/706,470**(22) Filed: **Sep. 20, 2019**(30) **Foreign Application Priority Data**

Jul. 24, 2019 (JP) 2019-016533
(51) **LOC (13) Cl.** **23-03**
(52) **U.S. Cl.**
USPC **D10/50**
(58) **Field of Classification Search**
USPC D10/46, 49, 50, 51, 52, 53; D13/123,
D13/133, 158, 162, 162.1, 163, 184;
D23/207
